COLLAPSIBLE WINDOW

Jay F. Johnson, Superior, Wis.

Application November 6, 1947, Serial No. 784,415

4 Claims. (Cl. 20—40)

1

This invention relates to windows such as disclosed in U. S. Patent No. 1,773,241 dated August 19, 1930.

The principal object of the instant invention is to make substantial improvements in such extendable and foldable windows to overcome certain undesirable features found in the former device.

Some of the defects in the prior device were that during cold weather the window glass would frost up making it impossible to see therethrough, and then too, there was the objection of the device being too cold to be comfortable due to lack of proper insulating construction. The operating means for the device was not fool-proof nor was adequate means provided to lock the parts in closed or open position except the weight of the individual parts.

Another object of the invention is to provide adequate novel means for control of the operable sashes of such windows in both open and closed position.

Another object is to provide an adequate frame for such windows as may be used on locomotive cabs whereby same may be readily applied thereto and operated conveniently from within said cab, it being desirable to be able to slide the window away from the window opening at times during the operation of a locomotive, especially while in the yards.

Other objects and advantages will appear as the description of the invention proceeds.

In the accompanying drawing forming a part of this application:

Fig. 1 is a perspective view of a window constructed in accordance with the invention showing the inside thereof.

Fig. 2 is a perspective view of the device from the outside thereof showing the same in partly folded position.

Fig. 3 is a side elevational view of Fig. 1.

Fig. 4 is a broken central sectional view through the upper portion of the window.

Fig. 5 is a broken perspective view of the lower portion of the control and catch means for the window in unlocked position.

Fig. 6 is a like view of the upper portion of the control and catch means for the window showing parts of the associated window in section therewith.

Fig. 7 is a sectional view through a portion of one of the side sashes approximately centrally of one of the slides and showing a cooperative portion of the central control sash.

Fig. 8 is an exploded view of the adjustable union of the central sash with the side sashes.

2

In the drawing the reference numeral 1 represents the major or outer frame of the device, which may, if desired, be a fixed part of a building or other structure, though, in the instant drawings, the device is shown as a portable foldable unit which may be applied to any window opening and being especially adapted for application to a locomotive cab window opening, the upper portion 2 and the lower portion 3 being telescopically united with the major frame so as to be readily adjustable for application to suitable channels, not shown, which are provided on locomotives in which their common sliding windows are installed. The major frame 1 has suitable hand grips 4 therein to permit of ready sliding of the device in said channels in the same manner as are the common cab windows.

Hingedly secured to the outer upper and side edges respectively of the major frame 1 are the top sash 5 and two side sashes 6—6, the side sashes being glazed as shown to provide visibility to each side of the device. On the inner lower edge of the major frame 1 is hingedly installed the bottom sash 7. It has been found that the so-called piano hinges are best suited to hinge the sashes to the major frame rather than spaced small hinges, the former giving smoother and easier operation than the latter as will be apparent to one skilled in the art.

The sashes are so hinged that they may be readily folded inwardly as indicated by the arrows in Fig. 2 of the drawing, they all being of a width to form a fitted rectangular window when extended.

Each side sash 6 has a horizontal guiding channel 8 adjacent the upper and lower inner edges thereof as clearly seen in the drawings. The purpose of these channels 8 is to provide means for slidably carrying the control sash 9, the connection between the control sash 9 and the side sashes 6 being as by a suitable slide such as illustrated at 10 in Figs. 7 and 8, the elongated flat body portion sliding easily within the channel 8 and the head or lug providing adequate connection to the control sash as by the recessed pin 11 to permit of the swinging inwardly thereof as shown in Fig. 2 when the control sash is in its innermost position. Obviously, some other suitable slide may be used if desired, but the provision must be made for the control sash 9 to be horizontally slidably carried by the two side sashes 6 in such a manner that all work freely as hereinafter set forth.

There being four channels 8, two in each side sash 6 in which four slides 10 operate, the control sash 9 is firmly supported thereby, the fitting

of the lugs on the slides 10 with the pins 11 on the control sash being sufficiently loose to permit of but slight tilting of the control sash which is necessary upon the initial closing of the extended window.

The control of the window resides in the control sash 9 and its connection to the side and bottom sashes. The connection of the side sashes to the control sash having already been defined, we will proceed with the description of the connection of the bottom sash to the control sash.

Fixed centrally of the bottom sash 7 on the inner wall thereof is an angle bracket 12, it having an elongated slot 13 therein as shown, and being bifurcated as at 14. Within the bifurcation is installed the body portion 15 of the lower slide member 16 as by the pin 17 which extends within the slot 13, the body 15 being fixed to the slide 16. Pivotally installed as by the pin 18 above the attaching pin 17 is the operating arm or lever 19 which is bifurcated centrally as at 20 to straddle the body portion 15 when in uppermost position. The lower end of the arm 19 is rounded off as at 21 to permit of ready action of the arm without interference by the bracket 12.

Pivotally installed within the bifurcation 20 of the arm 19 is the locking pitman 22, the same being installed sufficiently remote from the pin 18 as to permit the arm to completely straddle the body 15 in locked position. The locking pitman 22 is bent or offset as at 23 so that when the arm 19 is positioned against the slide member 16 the offset portion will lie within the bifurcation 24 of the slide 16 and will thus provide an offset snap lock arrangement for the purpose herein-after set forth.

The upper end of the pitman has a bifurcated portion 25 which is pivotally secured as at 26 to the lug 27 projecting from the upper slide 28 of the snap locking arrangement, the pivotal point 26 being substantially in the same plane as the pivot 18 of the arm 19, thereby insuring a positive snap locking action of the offset pitman when locked.

It is to be noted that the control sash 9 is made in substantially two separate equal parts, they being joined centrally only by the front or outer face member 29 of the control sash and a small rectangular facing plate 30 adjacent the upper edge thereof.

The two parts of the control sash are spaced slightly apart to make a channel 31 in which the pitman 22 may be operated and inwardly of the channel 31 adjacent the face member 29 of the control sash is a wider and thinner channel 32 which extends the full height of the control sash and in which the slides 16 and 28 operate vertically.

The connection of the control sash 9 to the bottom sash 7 is, as may be clearly seen, vertically slidable, but of such nature that the outer end of the bottom sash is always adjacent the control sash. This feature permits of the ready opening and closing of the device by manipulation of the handle 33 on the operating lever or arm 19.

The operation of the device is as follows: Assuming the window is in open position as shown in Fig. 1 of the drawing, all that is required to fold the same is to grasp the handle 33 and pull upwardly and inwardly. This will cause the outer edge of the bottom sash 7 to be raised, the slides 16 and 28 will be moved upwardly in the slot or channel 32, and the control sash 9 will be drawn inwardly, the bottom thereof leading the top slightly due to the inward pull being from

that portion and also to the fact that along the bottom face of the top sash 5 adjacent the outer edge thereof is a stop 34 which holds the upper portion of the control sash from falling inwardly when the device is in open position. The fact that the lower portion of the control sash moves inwardly ahead of the upper portion on the initial closing movement thereof, permits the upper portion to readily free itself from the stop 34 by presenting an inclined face thereto which, when pulled inwardly, will cause the top sash to lift enough to permit of the upper edge of the control sash passing thereunder.

As the control sash is moved inwardly by pulling upwardly and inwardly on the handle 33, the bottom sash 7 continues to be drawn or swung upwardly, the side sashes are drawn inwardly, and the top sash falls downwardly as clearly illustrated in Fig. 2 of the drawing, until all parts lie in a parallel plane. At this time the locking means is in unlocked position substantially as illustrated in Figs. 5 and 6 of the drawing.

The locking of the device is accomplished by swinging the lever 19 upwardly. The upper slide 28 is then moved farther upwardly by the pitman 22 until it extends upwardly beyond the upper edge of the control sash. Here it comes into contact with and engages the hooked end of the tongue-like catch member 35 which rests on the frame of the window when the device is in open position and as it is closed, the hooked end is moved upwardly into the slot 36 in the upper inner edge of the frame 1 as shown in dotted lines Fig. 4, the frame adjacent the slot 36 being bent upwardly as at 37 to insure such action. The outer end of the catch 35 is fixed to the inner face of the upper sash as shown.

As the lever 19 is swung farther upwardly towards locked position the slide 28 pushes the catch 35 farther into the slot 36 which pulls the top sash firmly against the closed side sashes holding them in firm closed position.

When the lever 19 finally straddles the body portion 15 the offset pitman snaps into locked position and is held there by the offset construction thereof. When the lock is thus snapped, the bottom sash 7 is held in fixed relation to the window frame and the control sash on one side, and the top sash 5 is held in innermost position in relation to the window frame against the side sashes on the opposite side to the bottom sash. This one locking arrangement then, holds the entire device in firm folded relation for easy transportation or whenever the window is in folded position or not in use.

It is to be noted that the glass of the control sash 9 and the side sashes 6-6 is double and set in a rubber gasket 38 to provide insulation and prevent the windows from frosting over in cold weather. This feature is especially essential when the window is to be used on locomotives where visibility is of extreme importance.

Each side sash has a lip 39 projecting inwardly along the outer edge thereof which limits the outward movement of the control sash and a lip 40 projecting inwardly from the lower edge thereof which limits the downward swing of the bottom sash thereby insuring a sturdy structure free from rattles.

Having thus described my invention, what I claim is:

1. In a foldable window, a frame, an upper sash, a lower sash, and two opposed side sashes hinged to and about the innermost edges of said frame, a central sash carried by said side sashes for con-

tral of all of said sashes, said side sashes having a pivotal and sliding connection with said control sash so as to be moved by the latter, said sashes being pivoted to extend in angular relation to said frame forming a box-like extension from said frame when in unfolded position and pivoted to extend in substantial alinement with said frame when in folded position, means for locking said sashes in closed position comprising a vertically reciprocable snap lock carried by and intermediate the bottom of one of said sashes and said central sash, a slide vertically operable by said snap lock and carried by said central sash, and a catch carried by the upper one of said sashes which is engageable by said slide to lock said sashes in closed position with said top sash overlapping said side and control sashes.

2. A foldable window comprising a frame, an upper sash, a lower sash, and two side sashes hinged to said frame on the inner edges thereof, a central sash slidably carried by said side sashes for control of all of said sashes, said sashes being pivoted to extend in angular relation to said frame forming a box-like extension from said frame when in unfolded position and pivoted to extend in substantial alinement with said frame when in folded position, a slide carried by said control sash and vertically slidably thereon, a lever pivotally carried by said slide, a pivotal attachment from said bottom sash to said slide, a pitman carried by said lever, an upper slide pivotally carried by said pitman and slidable on said central sash, and a catch carried by said top sash opposite to said last mentioned marginal sash which is engageable by said upper slide to hold all of said sashes in folded position when said lever and pitman are in locked position.

3. A foldable window comprising a frame; a

top, bottom, and two side sashes hingedly carried by said frame; a central sash slidably carried by said two side sashes and adapted to operate and control all of said sashes; said top, bottom, and side sashes being pivoted to extend in angular relation to said frame forming a box-like extension from said frame when in unfolded position and pivoted to extend in substantial alinement with said frame when in folded position; said central sash being laterally slidably mounted on said side sashes so as to be movable towards and away from said frame between said sashes; a vertically operable slide pivotally connected intermediate of said central sash and said bottom sash; a lever carried by said slide; an upper slide; an offset pitman connecting said upper slide to said lever; said slides being guided on said central sash; and a catch carried by said top sash and engageable by said upper slide; said lever being operable to move said upper slide into position to engage said catch to lock said window in folded position.

4. The structure as set forth in claim 3 and said window being foldable from open to closed position by pivoting said bottom slide upwardly on its pivotal connection to said frame so as to draw said central, side, and upper sashes inwardly toward said frame.

JAY F. JOHNSON.
